US0D1072573S

(12) **United States Design Patent** (10) **Patent No.:** **US D1,072,573 S**
(45) **Date of Patent:** **** Apr. 29, 2025**

(54) **TUMBLER**

(71) Applicant: **Zhejiang Lwwu Industry and Trade Co., Ltd.**, Zhejiang (CN)

(72) Inventor: **Caihe Long**, Hubei (CN)

(73) Assignee: **Zhejiang Lwwu Industry and Trade Co., Ltd.**, Jinhua (CN)

(**) Term: **15 Years**

(21) Appl. No.: **29/953,509**

(22) Filed: **Jul. 22, 2024**

(30) **Foreign Application Priority Data**

Mar. 19, 2024 (CN) 202430139955.X

(51) **LOC (15) Cl.** **07-01**

(52) **U.S. Cl.**

USPC **D7/533; D7/535**

(58) **Field of Classification Search**

USPC D7/507, 509-511, 540, 533-536, 300.1, D7/300.2, 316, 317, 391, 392.1, 396.1, D7/396.2, 629, 900, 500; D9/435, D9/530-531; D3/202

CLAIM

The ornamental design for a tumbler, as shown and described.

DESCRIPTION

FIG. 1 is a front perspective view of my new design for a tumbler;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded view thereof.

The broken lines depict portions of the tumbler and form no part of the claimed design.

1 Claim, 9 Drawing Sheets
